TAPPET

Games Slayter, Detroit, Mich.

Application November 15, 1930, Serial No. 495,937

1 Claim. (Cl. 123—90)

This invention relates to a tappet, such as is used in connection with valve operating mechanism in internal combustion engines, and has to do particularly with a novel manner of fabricating a tappet whereby to materially decrease its cost and at the same time increase its strength and durability in operation. Long experience in the fabrication of tappets by those in the automotive industry has proven that a cast iron tappet having chilled bearing surfaces is probably the best for all round use. A tappet formed completely of cast iron is not practical because, due to its size and design, it will not always stand the strain applied by the mechanic.

Many different ways have been proposed for strengthening the threaded end of the tappet to withstand the rough usage usually encountered at this point, and one method has been to spot weld a steel bearing jacket on to a cast iron head. While this has proven to be a practical solution of the problem, such a tappet has necessarily been relatively expensive to manufacture.

It is the object of the present invention to provide means for positively preventing cracking or twisting of the connecting end of the tappet when wrenches are applied to tighten the adjusting nuts in place. More specifically, the present invention embodies the use of a steel crown adapted to be so secured around the end of a tappet formed mostly of cast iron as to prevent cracking or twisting of the cast iron. In this case the steel jacket not only takes the greater part of the strain from torsional stresses applied to the tappet but acts as a band around the end thereof to reinforce and prevent any splitting at the point of application of the torsional stress.

In the drawing:

Fig. 1 is a longitudinal sectional view illustrating the manner of fabricating the cast iron tappet and one form of steel crown therefor.

Fig. 2 is an elevation, partly in section, of the assembled tappet.

Fig. 3 is a sectional view taken on line 3—3 of Fig. 2, and showing the preferred manner of cutting away a portion of the jacket and the cast iron wall whereby to receive a wrench or similar adjusting tool.

Fig. 4 is a fragmentary enlarged view, partly in section, and illustrating a modified form of jacket wherein the parallel sides are completely formed in the cast iron.

Fig. 5 is a sectional view illustrating a further modification wherein the steel jacket forms a threaded portion of the tappet but is connected

to the tappet at a point immediately adjacent the threaded portion.

Fig. 6 is a view similar to Fig. 3 but illustrating a modified manner of securing the steel jacket to the cast iron shell.

The gist of the present invention resides in the forming of the greater part of the tappet, and in fact substantially all of the tappet, of cast iron and the adding of a small inexpensive steel crown for positively reinforcing and holding the tappet as an integral unit at the point of greatest application of stress and strain. By forming the main body of the tappet of cast iron it is possible to chill the side walls as well as the head of the tappet if desired so as to present a very inexpensive but efficient bearing surface.

As shown in the embodiment illustrated in Figs. 1 and 2, my tappet preferably consists of a main body portion which may be generally designated 1. This body portion is formed of cast iron and having a standard head 2 with a chilled bearing surface 3 and cylindrical side walls 4 adapted to fit in the tappet sleeve. The interior of the cast iron body 1 may be cored out or drilled as at 5 and provided with the usual threads 6 for receiving the threaded end of the adjusting member as in standard practice.

The walls 4 of the tappet may or may not be chilled and ground to present an accurate bearing surface. It will be understood that if the walls 4 should be formed of steel as has been done in the past, it would be necessary to heat treat such steel surfaces to present the proper bearing surface. The threaded end of the tappet is preferably turned down as at 7 whereby to receive a steel crown 8. The cylindrical walls of this steel crown are held to very close dimensions so as to preferably have a press fit with the turned down walls 7.

It will be understood that the capping of the cast iron tappet with the crown 8 may be made by any well known method, that is, the crown may be sweat in place, it may be shrunk upon the walls 7, or it may have a press fit therewith. The manner in which the crown 8 is secured to the end of the cast iron tappet is immaterial as the important point here is that the end of the tappet is reinforced by a steel crown for positively preventing the same from splitting. The steel crown 8 is preferably provided with an inwardly extending counter-sunk portion and this entire steel crown, together with its accurately formed inner wall 10, presents a very inexpensive, easily machined unit.

In installing and adjusting a tappet, power

is usually applied at a point adjacent the threaded end thereof with the result that in the use of standard cast iron tappets excessive torsional stress placed on the end thereof frequently causes cracking. The steel crown 8 is therefore positioned only at the point where this destructive force is usually applied. The cast iron bearing walls of the tappet may be very easily chilled and ground.

10 In order to directly apply the torsional twisting effort to the cast iron body but at the same time compactly reinforce said body, I preferably cut away the steel crown as at 11 with the result that a wrench applied to the surface 11 will contact both with the cast iron body and the steel crown. It will thus be obvious that considerable torsional stress may be applied by the wrench but the end of the cast iron sleeve will be securely held against cracking by the steel crown.

15 20 In the modification illustrated in Fig. 6 I have shown the reduced wall 7 of the cast iron sleeve as being serrated whereby to cooperate with complementary serrations formed on the inner wall of the steel crown as shown at 12. In this case if the power should be applied only at points 13 the complementary serrations will prevent any

twisting of the crown relative to the cast iron body.

25 In the modification illustrated in Fig. 4 the cast iron body 1 is fabricated to include the cut away portions 14 for receiving a wrench, the steel crown 15 just having sufficient depth to cap the end of the cast iron body. In this case the steel crown takes none of the direct torsional stress applied by the wrench but acts solely as a reinforcing band for preventing cracking of the cast iron.

10 15 In the modification illustrated in Fig. 5 a steel crown 16 while still forming a relatively small part of the entire tappet is considerably longer than the crowns shown in Figs. 1 and 2. In this modification the bearing portion of the tappet is formed by the cast iron but a portion of the threads and the cut away surfaces for receiving the wrench are formed in the steel crown.

20 What I claim is:

A tappet having the greater portion thereof formed of cast iron, a steel crown for one end of said tappet and bearing surfaces formed partly by said cast iron and partly by said crown for receiving an adjusting tool.
